UNITED STATES PATENT OFFICE.

DANIEL M. WINANS, OF BINGHAMTON, NEW YORK, ASSIGNEE TO THE BREWER-TITCHENER CORPORATION, OF BINGHAMTON, NEW YORK, A CORPORATION OF NEW YORK.

DETACHABLE LIGHT FOR VEHICLE-CURTAINS.

1,337,302.

Specification of Letters Patent.

Patented Apr. 20, 1920.

Application filed July 5, 1918. Serial No. 243,414.

To all whom it may concern:

Be it known that I, DANIEL M. WINANS, a citizen of the United States, residing at Binghamton, in the county of Broome and

5 State of New York, have invented certain new and useful Improvements in Detachable Lights for Vehicle-Curtains, of which the following is a specification.

This invention is an improvement on the 10 detachable light set forth in my application, Serial No. 204945, filed Dec. 1, 1917.

One object is to decrease the number of 15 elements which have to be assembled when applying the light to a vehicle curtain, thereby saving time and labor in attaching the light to the curtain.

This object is accomplished by providing a back-ring and pane or light which are self-contained with each other, that is, the 20 pane is carried by the back-ring as a unitary structure which can be applied, as such, to the inner face of the curtain, ready for the connection thereto of the outer frame which appears on the outer face of the curtain.

25 The manner of attaching the pane or light to the back-ring is susceptible of variation, one embodiment only being set forth hereinafter and shown in the accompanying drawings.

30 Another object is to securely hold, or grip, the curtain to provide a non-leaking or non-spreading joint between the back-ring, outer frame, and curtain.

To that end, the back-ring and outer frame 35 are so formed that they will telescope and pinch the curtain between themselves in such manner that flapping of the curtain, jars and jolts to which it is subjected due to travel of the vehicle over rough roads, 40 and other strains will not result in slippages of the parts, nor open spaces between the ring and frame and the curtain but, on the other hand, the joint will be substantially water-tight.

45 A further object is to provide improved means for engaging the screws that hold the outer frame and back-ring together, whereby any tendency of the frame and ring to become distorted by reason of excessive 50 tension due to the tightness of the screws,

will be minimized, and probably entirely prevented, thereby minimizing liability of occurrence of spaces between the frame and ring and curtain.

This object is carried out by the provision 55 of flanges on the outer frame which have projections engaging the nuts with which the screws engage. In that connection, I provide flat nuts whose edges lie under the flanges and are held by the projections 60 aforesaid. Such projections may be provided in the form of punched-up parts or raised nibs which do not break the continuity of the flanges and hence no open spaces are possible between the outer frame and the 65 curtain. Furthermore, such manner of securing the nuts may be had by a machine operation, thus greatly decreasing the time and work necessary to secure the nuts to the outer frame. 70

My present improvements in the back-ring and outer frame, enable these parts to be made as stampings which lessens the expense of production and insures uniformity of dimensions and permits interchangeability. 75

The unitary form of the back-ring and the pane or light not only facilitates application to the curtain, but insures against slippage of the pane and any rattling of the 80 same.

The invention being susceptible of modification, the present disclosures are not to be considered as restrictive of the scope of the invention. 85

In the accompanying drawings:

Figure 1, is a view looking toward the outer frame and outer face of the pane, as applied to a curtain, a portion of which is shown, certain parts being broken away to 90 disclose the part of the curtain which is held by the frame and ring, and to show the back-ring;

Fig. 2 is a front view of the unitary back-ring and pane or light, showing how the 95 latter is held by the former;

Fig. 3 is a similar view looking toward the inner face of the outer ring, showing the nuts and the manner of securing them;

Fig. 4 is a detail view of one of the pane- 100

holding devices carried by the back-ring, before it has been bent down to secure the pane;

5 Fig. 5 is a detail cross-section through the pane, curtain and pane-holding means;

Fig. 6 is a similar view, taken at another point, showing the manner in which the pane is held by the back-ring so as to be a unitary structure therewith;

10 Fig. 7 is a detail face view showing one of the nuts and the means for holding the same;

Fig. 8 is a view like Fig. 5, showing a nut such as disclosed in my application, Ser. 15 No. 204945;

Fig. 9 is a face view of the nut of Fig. 8, and the holding means therefor.

20 A portion of the curtain of an automobile or other vehicle is shown at 1, and the pane or light at 2. I have illustrated a beveled plate-glass pane, but the invention is intended for use in connection with celluloid panes or any transparent pane.

25 The pane is unitary or self-contained with a back-ring 3 and there is an outer frame 4. The present pane 2 being oval, the ring 3 and frame 4 are of that shape. I wish it understood, however, that the pane 2 may be circular, rectangular, or of any other 30 shape, and that the ring 3 and frame 4 will vary in shape according to the shape of the pane. I do not limit myself to a ring, frame and pane of any particular shape and intend to embrace all shapes to which the invention is adaptable.

35 The ring 3 and frame 4 are of metal, preferably stampings, to insure lightness, strength, cheapness of manufacture, and uniformity. The ring 3 and frame 4 are of 40 arched form in cross-sectional shape.

45 The pane 2 may be secured to the back-ring 3 in different ways, one of which is shown. Clips, in the form of stampings 5 (Fig. 4) are connected to the inner face of the ring 3 and, when the pane 2 has been laid on the inner flange 6 of the ring, these clips have their ears 7 bent down to engage the edge of the pane as shown in Figs. 2 and 6. The pane is then, to all intents and purposes, a unitary structure with the back-ring 50 3 and the two comprise but one element when it comes to applying them to the curtain or removing them therefrom, thereby saving much time and labor over a structure where the pane and ring are separate.

55 The clips may be secured to the back-ring in different ways, such as by spot-welding, or soldering, the latter manner being illustrated, the solder being shown at 8, Fig. 6, as occupying the space or opening in the clip after the ear 7 has been struck up. The 60 clips are in the form shown in Fig. 4 when supplied to the assembler for connection to the ring 3.

65 The outer edge of the back-ring 3 is pro-

vided with a flange 9 which admits telescoping with the outer frame 4 as will appear from Figs. 5 and 6. The curtain 1 is, consequently, pinched between the ring and frame, as shown in Figs. 5 and 6, and a 70 water-tight joint thus provided which is not impaired by the flapping, jarring, and straining to which a vehicle curtain is subjected. Preferably, the flange 9 flares outwardly, but I do not limit myself to any particular angle.

75 In Fig. 9, I have shown how the outer frame 4 may be provided with nuts 10 similar to those disclosed in my application, Ser. No. 204945, and held by ears 11 bent 80 down from the edges of the frame and entering notches 12 in the nuts 10, screws 13 being provided which pass through holes 14 in the back-ring 3 and engage the screw-threaded holes 15 in the nuts, for the purpose of securing the back-ring and frame together. Those parts of my present invention relating to the unitary arrangement of the back-ring and the pane, and the telescoping of the outer frame and back-ring being 85 complete improvements, I have illustrated the nuts 10 of my earlier application to show that said improved features are not dependent on the improved nut and means on the outer frame 4 for its securement.

90 The improved nut 16 shown in Figs. 3, 5, and 7 is preferred as it is more simple, cheaper, and more readily assembled with the improved holding means comprising the flanges 17 and 18 which I have provided on 95 the outer frame, than the arrangement of nut and holding ears shown in Figs. 8 and 9. It is to be understood, however, that the flanges 17 and 18 could be employed to hold a nut such as the nut 10 of Figs. 8 and 9.

100 In Figs. 3, 5, 6 and 7 the outer frame 4 has continuous flanges 17 and 18 which not only hold the nuts 16, but afford a relative wide and firm bearing for the curtain 1 and materially assist in pinching or clamping it 105 and rendering the joint between the ring and frame and curtain more secure than is possible with a narrow edge such as shown in Figs. 8 and 9. The nuts 16 are flat and have their edges lying under the flanges 17 and 18. 110 Nibs, depressions, or projections 19 are formed in the inner edges of the flanges 17 and 18 on opposite sides of the nuts, as shown in Fig. 7, thus securely holding the nuts without resort to solder or other securing means. The nuts could be provided with depressions to receive the projections 19, instead of locating the latter where they 115 will engage the edges of the nuts.

120 The screws 13 passing through holes 14 in 125 the back-ring, engage screw-threaded holes 15 in the nuts 16, as in Figs. 8 and 9, previously described. The flat flanges 17 and 18, and the adaptability of the back-ring and outer frame to telescope, insure against 130

separation of either the ring or the frame from the curtain no matter how tightly the screws may be arranged, as the curtain is engaged by a relatively wide surface on both 5 sides and is securely pinched between the ring and frame.

What I claim is:

A detachable "light" for vehicle curtains, comprising a ring having inner and outer 10 flanges arranged angularly to the plane of the ring and spaced apart, and a pane whose marginal portion bears on the inner flange aforesaid and is spaced from the outer flange, means being provided on the ring 15 for securing the pane against said inner

flange and holding it unitary with said ring, said pane and ring being permanently connected together and attachable as a unitary structure to the curtain, or removable as a unit therefrom, a frame adapted to be positioned on the opposite side of the curtain from the ring and pane and to telescope into the space between the margin of the pane and the outer flange of the ring so as to pinch the curtain between them, and screw 20 fastenings for detachably securing the ring and frame together with the curtain clamped therebetween.

In testimony whereof I affix my signature.

DANIEL M. WINANS.
